UNITED STATES PATENT OFFICE.

SARAH JANE SHIELS, OF NEW YORK, N. Y., ASSIGNOR TO THE BUTTERICK PUBLISHING COMPANY, (LIMITED), OF SAME PLACE.

DESIGN FOR A LADY'S COSTUME.

SPECIFICATION forming part of Design No. 15,026, dated May 27, 1884.

Application filed March 27, 1884. Term of patent 3½ years.

To all whom it may concern:

Be it known that I, SARAH JANE SHIELS, of the city, county, and State of New York, have invented and produced a new and original Design for a Pattern of a Lady's Costume, (numbered 9,165;) and I do hereby declare that the engraved prints accompanying this specification convey to any one accustomed to using paper patterns a clear understanding of how a garment made up by the pattern will appear.

The design shows a round walking-skirt and an overdress. The skirt displays a narrow panel upon each side of the front. The over-dress exhibits closely-fitted basque-fronts falling in pointed tabs back of the closing, narrow under-arm gores extending in broad panels

nearly to the bottom of the skirt, a closely-fitting back that displays a pointed upper drapery exhibiting drapings at the center and front edges, and a deep square under drapery 20 also exhibiting drapings, coat-sleeves, a standing collar, and a lapel-collar.

What I claim as my invention, and desire to secure by Letters Patent, is—

The design for a lady's costume, as shown in 25 the engraved prints accompanying this specification.

SARAH JANE SHIELS.
